Edward S. Burbank

UNITED STATES PATENT OFFICE.

EDWARD S. BURBANK, OF OMAHA, NEBRASKA.

JEWELER'S TAG.

SPECIFICATION forming part of Letters Patent No. 374,823, dated December 13, 1887.

Application filed February 2, 1887. Serial No. 226,330. (No model.)

To all whom it may concern:

Be it known that I, EDWARD S. BURBANK, a citizen of the United States, residing at Omaha, in the county of Douglas and State of Nebraska, have invented new and useful Improvements in Watch-Repair Tags, of which the following is a specification, reference being had to the accompanying drawings.

My invention relates to an improvement in watch-repair tags; and it consists in the peculiar shape and other details, which will be more fully set forth hereinafter, and particularly pointed out in the claim.

In the drawings, Figure 1 is a side view of the tag embodying my improvements. Fig. 2 is a side view of the tag attached to the watch. Fig. 3 is a vertical view of the same. Fig. 4 is a detail view of attaching device. Fig. 5 is a view showing that both edges of the tags conform with each other.

A curved tag is represented in Fig. 1 provided with the attaching-band A, extending to one side at an angle of about one hundred degrees from the body of the tag, the loop-hole 25 B being the center.

Fig. 4 represents the device attached. The tags are temporarily attached to the watch by passing the attaching-band A through the watch-bow L, then drawing it around and inserting it through the loop-hole B to C, and the tag is securely attached by then drawing the attaching-band A around the inner edge of tag at H and again inserting through the loop-hole B to F. Letter E represents the 35 back of the attached tag.

The object and novelty of my invention will be more fully understood from the foregoing description and accompanying drawings.

First. By providing the tag with an attaching-band extending to one side and curved at 40 an angle corresponding with the curve of the watch case and bow the tag hangs normally and diagonally across the watch, which serves to some extent as a protection, preventing the watches from scratching each other when 45 placed side by side in the drawers of the safe. Second. These tags never tangle together nor catch to rack-hooks and watch-chains, and can be temporarily attached as well as more securely attached, and are readily detached by 50 drawing out the loop-band or breaking off the tag when wanted no longer. They are made of tough check and Manila board, and are a most convenient and serviceable watch-repair tag. 55

Having thus described my invention, I claim—

The curved tag provided with the attaching-band extending to one side thereof, substantially as described. 60

In testimony that I claim the foregoing as my own I have hereto affixed my signature in presence of two witnesses.

EDWARD S. BURBANK.
